UNITED STATES PATENT OFFICE.

HARRISON H. BOYCE, OF FOREST HILLS, NEW YORK.

DESIGN FOR A FLUID CONTAINER FOR FIRE EXTINGUISHERS.

60,511.

Specification for Design.

Patented Mar. 7, 1922.

Application filed April 12, 1920. Serial No. 373,393. Term of patent 14 years.

To all whom it may concern:

Be it known that I, HARRISON H. BOYCE, a citizen of the United States, residing in Forest Hills, county of Queens, and State of New York, have invented a new, original, and ornamental Design for a Fluid Container for Fire Extinguishers, of which the following is a specification, reference being had to the accompanying drawing, forming a part thereof.

Figure 1 is an elevation of a container embodying my invention;

Figure 2 is a top plan view thereof.

What I claim is—

The ornamental design for a fluid container for fire extinguishers, as shown.

HARRISON H. BOYCE.
